BOOTH FOR DICTATION EQUIPMENT

John J. Schumacher, Akron, Ohio, assignor to Travel
Talk, Inc., a corporation of Ohio

Application November 4, 1953, Serial No. 27,451

Term of patent 14 years

(Cl. D33—19)

FIG. 1

FIG. 2

Des. 176,289

PAGE 2

FIG. 3

FIG. 4

FIG. 5

Fig. 1 is a front perspective view of a booth for dictation equipment, showing my new design;

Fig. 2 is a side elevational view thereof with the legs omitted for convenience of illustration only;

Fig. 3 is a cross-sectional view taken on the line 3—3 of Fig. 5, with the leg elements omitted as in Fig. 2;

Fig. 4 is a front elevational view of the booth with the legs omitted as in Fig. 2; and

Fig. 5 is a top plan view thereof.

The characteristic features of the design are shown in solid lines.

I claim:

The ornamental design for a booth for dictation equipment, as shown and described.
